UNITED STATES PATENT OFFICE.

CAROLINE B. KELLEY, OF PHILADELPHIA, PENNSYLVANIA, ASSIGNOR TO
R. BLANKENBURG & CO., OF SAME PLACE.

DESIGN FOR AN EMBROIDERY-PATTERN.

SPECIFICATION forming part of Design No. 33,722, dated December 11, 1900.

Application filed November 8, 1900. Serial No. 35,867. Term of patent 3½ years.

To all whom it may concern:

Be it known that I, CAROLINE B. KELLEY, a citizen of the United States, residing in Philadelphia, Pennsylvania, have invented and produced a new and original Design for an Embroidery-Pattern, of which the following is a specification.

My design for an embroidery-pattern is fully set forth in the accompanying drawing, where it is shown as formed upon a piece of fabric.

In the center of the pattern is the representation of an American bison or "buffalo," shown as standing upon a portion of a terrestrial globe, the latter projecting from a mass of clouds. Above the buffalo are two draped flags having their sticks crossed, and disposed between the flags is an eagle, its talons grasping a leafy branch, while from its beak a

streamer floats. Between the buffalo and the eagle and covering a portion of the flags is a panel formed by curved lines, with depending end projections and scroll-like upper corners. Upon either side of the design and projecting toward the center from the end projections of the panel are ribbons or streamers.

I claim—

The design for an embroidery-pattern, substantially as described and as shown in the accompanying drawing.

In testimony whereof I have signed my name to this specification in the presence of two subscribing witnesses.

CAROLINE B. KELLEY.
